UNITED STATES PATENT OFFICE.

CHARLES S. JOHNSON, OF CHAMPAIGN, ILLINOIS.

OVERHEAD MEASURING AND LOADING CONSTRUCTION.

Application filed May 26, 1923. Serial No. 641,692.

To all whom it may concern:

Be it known that I, CHARLES S. JOHNSON, a citizen of the United States, and a resident of Champaign, county of Champaign, and 5 State of Illinois, have invented a certain new and useful Overhead Measuring and Loading Construction; and I do hereby declare that the following is a full, clear, and exact description thereof, reference being 10 had to the accompanying drawings, in which like numerals refer to like parts.

The object of this invention is to furnish an overhead measuring and loading construction for sand, gravel, crushed stone for 15 concrete, and other loose material, the parts of which are made in units that may be readily transported, readily assembled to make a rigid sturdy structure and readily disassembled as required.

20 Another object is to provide such construction with a receiving bin mounted removably on a pair of "horses" separated to admit the passage between them of a truck or wagon to be loaded, and providing at 25 the lower discharge end of the bin measuring hoppers, preferably two pairs of them, provided with valve mechanisms for controlling the discharge thereof, and a platform on each support for an operator to stand and be in position to operate the valve or valves and be able to observe that the measuring hoppers are always full, before 30 operating the discharge valve or valves.

It is well known that a great amount of 35 labor and expense is involved in hauling large bulks of road-building material and the like at much inconvenience and loss of time by the methods employed heretofore. By providing a structure and equipment 40 such as herein described and illustrated, much labor, cost and time is saved, because the bunkers, although large in order to contain great bulks of such materials, can be readily moved about and changed in position and set up close to the scene of operations, be filled from railway cars at railway sidings, and the material withdrawn in measured quantities into trucks for transportation to the place for use. Road work 45 and other work requiring loose building materials capable of flowing by gravity, may thereby be continued without interruption at considerable distances from the place of installation of the bunkers, and the latter may

be moved to other vantage points as the 55 work proceeds and be again set up with a minimum loss of time. Also the measuring hoppers are readily operable by a single workman who is always in position to be sure that the hoppers are full before discharging the contents, and thus accurately 60 measure the materials handled.

The foregoing and other important novel features of this invention will be more fully understood from the accompanying drawings 65 and the following description and claims.

In the drawings, Fig. 1 is a vertical transverse section through said construction, with the bin in elevation however, and a truck 70 in position to be loaded, indicated in dotted lines. Fig. 2 is a section on the line 2—2 of Fig. 1. Fig. 3 is a side elevation of the bin. Fig. 4 is a vertical central transverse section through the bin and outlet mechanism. Fig. 5 is an elevation of discharge 75 hopper and valve means for the storage bin, parts being broken away. Fig. 6 is an elevation of the lower end of the measuring 80 hopper, and its discharge controlling means, parts being broken away.

Briefly and broadly stated, said measuring and loading construction consists of a pair of supports or "horses" 10 mounted on a layer of planks 11 on the ground 12 and 85 a skeleton structure or cradle 13 supported on the horses which carries a storage bin 14 for receiving the material, with one or more measuring hoppers 15 to receive the material from said bin and located below the 90 same in position to discharge into a truck 16 below, the discharge being controlled by a valve mechanism 17 operated by the workman standing on the platform 18 on one of the horses 10 located so that he can see 95 readily the tops of the measuring hoppers and determine whether or not they are full and to close the upper valve mechanism 19 when the measuring hoppers are full.

Since one of the features of this invention is the ready removability, transporting and assembling at any desired place, said structure, I smooth the ground and lay a series of planks 11 thereon, side by side, like a bridge. Upon the planks I locate the 100 horses near each end of the plank foundation, and so that the planks extend under both horses. This gives a steady support 105

for the horses and one very economically made, and also furnishes a good foundation for the trucks to run in between the horses and have the top of the truck bed always about the same distance from the measuring hoppers and properly centered with relation to the hoppers, so that the material therefrom, in discharging by gravity, will always fall into the truck bed. The centering of the truck with relation to the measuring hoppers is predetermined by the positions of the two horses, they being located so as to permit the passage between them of the truck and yet not allow sufficient lateral displacement of the truck to cause any of the material to be discharged outside of the truck bed. The storage bin at the top of the structure is hopper-shaped and composed of inclined sides 20 and vertically-disposed ends 21 adapted to interlock, as shown in Fig. 4. Each of the sections 20 is composed of horizontally disposed planks secured to upwardly inclined braces 22 on the outside thereof, see Figs. 2 and 4; and on the inside, there are end cleats 23 against which the vertical sections 21 are placed, as seen in Fig. 2. The vertical sections 21 are composed of vertical planks secured to horizontal bars 24 at the top, bottom and middle thereof. In assembling these sections of the bin, the end sections 21 are placed on and against the side sections 20 and rest against the inside end cleats 23 of the side sections, as shown in Figs. 2 and 4.

When two sorts of material are desired to be handled and used together, as for instance "stone" and "sand" in mixing concrete material, the bin is divided into two compartments, a stone compartment and a sand compartment, by a partition formed of the members 30 and 31, as seen in Fig. 4. The upper partition member 30 is located so that its upper portion will be about midway between the ends of the bin and it inclines downwardly and outwardly towards the sand section and abuts against the upper end of the partition member 31, which is inclined in the opposite direction, and at its lower end extends to a point about midway between the sides of the outlet of the bin. This furnishes two bin sections with substantially equal inlets at the upper end to receive the materials, but the capacity of the two bin sections differs. In Fig. 4, as shown, the "sand" section is of smaller capacity than the "stone" section.

The bin is mounted on the frame heretofore referred to as frame 13 or "cradle." The cradle frame as herein shown consists of horizontal side beams 35 adapted to rest in the channel beam 36, as seen in Fig. 1. Cross beams 37 are secured upon the side beams 35. Vertical brace bars 38 extend vertically from each end of each end beam 35 and the adjacent cross beam 37, and an upper set of

cross beams 40 extends between and are connected with the uprights 38 and are parallel with the cross beams 37. This makes a rectangular frame, which is also part of the cradle frame. The hopper-holding portions of said frame consist of inclined bars 41 centrally mounted on the upper ends of the upright bars 38 by the triangular plates 42. The lower ends of the bars 41 extend down through the rectangular frame and are secured to the beams 37 and 40, and are strengthened by the triangular plate 43 riveted to the bar 40 and to the short inclined brace 44 extending outwardly at right angles to the bar 41 and secured to both the beams 37 and 40. The upper ends of the bars 41 are secured to side braces 45 by angle plates 46. The braces 45 extend from the side bottom beams 35 and are secured to the ends of the cross beam 37 by the plate 45. This brace 45 is inclined upwardly and outwardly, as shown in Fig. 1. There are cross channel irons 47 and 48 fastened to the triangular plates 42 and 46 and to the bars 41, as shown in Fig. 3. As seen in Fig. 3, there are two bars 41 on each side of the machine. There are also on the sides, as seen in Fig. 3, inclined braces 50 secured to the brace plates 51 at their lower ends and a brace plate 52 at its upper end. The plate 52 is fastened to the horizontal bar 47. The plates 51 are fastened to the beams 35 and vertical bars 38 and 45.

The bars 47 and 48, as shown in Figs. 1 and 3, are set back of the faces of the bars 41 and serve as supports for the inclined side member of the bin, the bars 22 of the bin frame resting on the cross bars 47 and 48 of the cradle frame and the cross planking 20 resting against the inclined bars 41. This arrangement enables the inclined side portions of the bin to rest by gravity on the side portions of the cradle frame, the end portions 21 of the bin to be inserted between the side portions of the bin. These parts all interlock and are not secured to each other. Hence they can readily be put together or separated.

At the outlet of the bin, as seen in Figs. 1 and 2, there is a metal dish-shaped frame formed of side plates 55 and a bottom plate 56. The side plates 55 are secured to the bars 40, as seen in Fig. 1, and the lower end of the bin is inserted in the upper part of said dish-shaped frame so as to discharge therein. The bottom of said dish-shaped frame has four outlets 57, two for each chamber in the bin. In Fig. 4 two of these four outlets appear. There is also an I beam 58 transversely of the dish-shaped frame 55 on which the lower end of the partition 31 is located, as seen in Fig. 4. The dish-shaped frame 55 and the I beam 58 are all riveted to the other parts of the cradle frame so as to be rigid.

Under each outlet 57 from the bin, there is a measuring hopper 15, see Figs. 1 and 3. The two of these for the sand bin are smaller than the two for the stone bin, their capacities being substantially in proportion to the relative proportions of sand and stone to be combined in making concrete. Because less sand is desired than stone, the sand section of the bin is smaller than the stone section 10 thereof.

These measuring hoppers are doubly conical and are mounted in the rectangular portion of the cradle frame heretofore described. Their details constitute no new 15 part of this invention, and, therefore, they need not be set forth herein.

The outlets from the bin are controlled by hand-operated valves 19 mounted at the bottom of the dish-shaped frame 55 by the 20 hoppers 66. The arrangement of the valve 19 is shown in Fig. 5. The valve 19 is pivoted on the pivot 70 and has a shank 71 extending therefrom to which the handle 68 is fastened. The exact nature of this valve 25 is immaterial in this invention, but it may be stated that the construction herein shown may be operated in pairs, one of the stone valves 19 being connected with one of the sand valves by a connecting rod 67, and said 30 pair of valves being operated by the hand lever 68. Consequently there would be two sets of these valves and two hand levers 68.

There are also valves 17 controlling the outlet of the measuring hoppers 15, see Figs. 35 1, 3 and 6. These valves are hinged at 75 to a frame 76 secured to the hopper, so that the valve when opening, drops downward instead of being turned laterally like the valves 19. There is a rib plate 77 secured 40 to the valve which is connected by a toggle link 78 with a hand lever 79 pivoted at 80 to the frame 76. There is another hand bell crank lever 81 pivoted at 80 and connected by a connecting rod 82 with a bell crank 45 lever 83 mounted on the frame 76 secured to the other measuring hopper 15 of the pair, as seen in Fig. 1. A link 84 extends from the lever 83 to the plate 77 on the valve 17 for such other measuring hopper. The 50 lever 79 has secured to it a stop arm 85 adapted to engage the frame 76 and limit its movement when the valve 17 is closed. The lower ends of the hoppers are held in 55 relative position by a connecting rod 90 secured to and extending between them, and braces 91 extend centrally from the lower part of the cradle frame to each end of the horses 10 for holding the latter in place relative to the super-structure. The channel beam 36 on the upper end of each horse 60 is mounted on an I beam 92, said I beam and channel beam together giving a very rigid construction for the upper ends of the horses and for the support of the super-structure. After the tie rods 91 are re-

leased, the super-structure can be removed by merely lifting it up from the channel beam; in other words, the super-structure is held in place in the channel beam by gravity just as the bin is held in place in the cradle frame by gravity.

The platform 18 is provided on the inside of each horse near the middle thereof, consisting of a plank support on cross bars 94 in position for a man to stand on the 75 plank or platform for operating the valves, and also observation being enabled to determine that the measuring hoppers are full. In other words, a man standing on the plank 18 will be in the right position for operating the levers 79 and 81 by hand and his head will extend up into the hollow rectangular frame almost to the upper beam 40, so that his eyes will be on a level with the tops of the measuring hoppers. He can then be sure that the measuring hoppers are full before he closes the upper valves 19. When he opens said valves, the stone and sand flow by gravity into the hoppers until 80 they are full. Then he closes the valve 19 and opens the lower valves, whereupon the material in the hoppers descends by gravity into the truck bed 16 below. When the measuring hoppers have discharged the 85 contents, he closes the lower valves and opens the upper valves. This is repeated until the vehicle is loaded. One man can operate the valves for all four of the measuring hoppers from one platform 18; in this manner the mechanism is easily operated 90 and the material is discharged into the wagon by measurement and by proper proportion. There is a fender bar 95 secured to each horse at the lower end in position to engage the truck wheels and properly 95 center the truck bed under the measuring hoppers and keep the truck bed from engaging the platforms 18.

In assembling the structure, the ground 100 is first smoothed at the desired location and the planks 11 laid side by side sufficiently wide for the horses and truck. Then the horses are placed thereon sufficiently far apart to receive the cradle frame above. The cradle frame is then placed on the 105 horses and the braces 91 put in place and tightened. Then the side sections of the 110 hopper are laid in on the inclined portions of the cradle frame and the front and back portions of the hopper placed in upon the side portions thereof. This completes the 115 assembly without any bolts or other means for fastening the parts of the structure together. They are held in place by gravity 120 because they are constructed so as to hold them. This enables the structure to be readily disassembled and transported on a truck to some other place. By reason of 125 said construction, the structure can be readily located anywhere desired, or changed in 130

position and readily operated. One workman on one of the platforms 18 can operate all the valves for loading the trucks as they are driven under the measuring hopers, one after the other.

The invention claimed is:

1. A structure for loading loose material including a pair of supports between which the vehicle to be loaded may stand, a frame resting upon the upper ends of said supports, and a bin resting upon said frame, said members being held together by gravity, and the adjacent parts thereof interlocking to prevent displacement, whereby they can be readily assembled, disassembled and transported as desired. 70
2. A structure for loading loose material including a pair of horses between which the vehicle to be loaded may stand, a frame resting upon the upper ends of said horses, a bin resting upon said frame, said members being held together by gravity, and the adjacent parts thereof interlocking to prevent displacement, and a platform on the ground formed of transversely extending planks adjacent each other and on the ends of which planks said horses rest by gravity, whereby they can be readily assembled, disassembled and transported as desired. 75
3. A structure for loading loose material including a pair of horses between which the vehicle to be loaded may stand, a frame resting upon the upper ends of said horses, a bin resting upon said frame, said members being held together by gravity, and the adjacent parts thereof interlocking to prevent displacement, and removable diagonal braces connecting the upper part of the horses to the central part of said frame, whereby they can be readily assembled, disassembled and transported as desired. 80
4. A structure for loading loose material including a pair of horses between which the vehicle to be loaded may stand, the upper ends of the horses having each a longitudinally extending channel beam, a frame having under each side thereof a beam adapted to rest by gravity in said channel beam on the horse below it, and a bin resting upon said frame, said members being held together by gravity and the adjacent parts thereof interlocking to prevent displacement. 85
5. A structure for loading loose material including a pair of horses between which the vehicle to be loaded may stand, the upper ends of the horses having longitudinally extending channel beams, a frame having under each side thereof a beam adapted to rest by gravity in said channel beam on the horse below it, a bin resting upon said frame, said members being held together by gravity and the adjacent parts thereof interlocking to prevent displacement, and diagonal braces connecting the upper part of the horses to the central part of said frame, in both the front and rear structure. 90
6. A structure for loading loose material including a pair of lateral supports between which the vehicle to be loaded may stand, a cradle-shaped frame with its ends resting on said supports, the inner sides of said frame being inclined downwardly towards each other, and a downwardly tapering bin resting on and in said cradle-shaped frame with a central outlet in the lower part thereof, said members being held together by gravity and the adjacent parts thereof interlocking to prevent displacement. 95
7. A structure for loading loose material including a pair of lateral supports between which the vehicle to be loaded may stand, a cradle-shaped frame composed of a lower rectangular frame adapted to rest by gravity upon said supports and with upwardly and outwardly inclined sides secured to and extending from the rectangular portion of the frame, and a downwardly tapering bin resting on and in said cradle-shaped frame with a central outlet in the lower part thereof, said members being held together by gravity and the adjacent parts thereof interlocking to prevent displacement. 100
8. A structure for loading loose material including a pair of lateral supports between which the vehicle to be loaded may stand, a cradle-shaped frame adapted to rest upon said supports formed with upwardly extending beans at each end of the sides, and intermediate transverse beams secured to said end beams and set back from the face of said end beams, and a hopper including inclined side sections adapted to be loosely placed on the inclined sides of said cradle frame, said hopper section being formed of longitudinal boards which bear against the end bars of the sides of the cradle frame, and upwardly extending bars secured to the planking of the bin and bearing against the cross bars of the side of the cradle frame so that the side of the cradle frame will directly contact with and support both the horizontal planking and the upright bars of the bin section. 105
9. A structure for measuring loose material and loading it including a pair of lateral supports between which the truck to be loaded may stand, a frame loosely mounted upon the upper ends of said supports, a V-shaped bin loosely mounted upon said frame with two outlets at the lower end, a partition in the bin dividing it into two unequal compartments, one adapted to discharge through each outlet, and a measuring hopper mounted in said frame for each outlet, the measuring hopper for the smaller compartment of the bin being relatively smaller than the measuring hopper for the other compartment of the bin. 110

10. A structure for measuring loose material and loading it including a pair of laterally placed supports between which the truck to be loaded may stand, a frame 5 loosely mounted upon the upper ends of said supports, a V-shaped bin loosely mounted upon said frame with outlets at the lower end, a measuring hopper for each outlet mounted in said frame, valve mechanism for controlling the inlet of material to the hoppers, valve mechanism for controlling the outlet of material to the hoppers, and a platform on the inside of each support upon which the workman may stand and in position to enable him to operate said valves and also see if the hoppers are full before they are discharged. 20 25 30
11. A structure for measuring loose material and loading it including a pair of laterally placed supports between which the truck to be loaded may stand, a frame 15

In witness whereof, I have hereunto affixed my signature.

CHARLES S. JOHNSON.
